UNITED STATES PATENT OFFICE.

CHRISTOPHER C. BRADLEY, OF SYRACUSE, NEW YORK.

MOWING-MACHINE.

SPECIFICATION forming part of Letters Patent No. 329,709, dated November 3, 1885.

Application filed April 1, 1884. Serial No. 126,313. (No model.)

To all whom it may concern:

Be it known that I, CHRISTOPHER C. BRADLEY, of the city of Syracuse, in the county of Onondaga and State of New York, have invented new and useful Improvements in Mowing-Machines, of which the following is a specification.

This invention relates to an improved construction of the parts whereby the shoe at the inner end of the cutter mechanism is adjustably connected with the main frame; and it has the object to construct these parts in a simple, strong, and durable manner, and so that the parts can be easily adjusted, at the same time protecting the connecting-rod of the cutter mechanism against stones and other obstacles which may be in the way and relieving the shoe from a large portion of the weight, thereby rendering the movements of the machine easy.

My invention consists, to these ends, of the improvements which will be hereinafter fully set forth, and pointed out in the claims.

In the accompanying drawings, consisting of three sheets, Figure 1 is a top plan view of a mowing-machine provided with my improvements. Fig. 2 is a fragmentary sectional front elevation of the machine. Fig. 3 is a sectional side elevation of the machine. Fig. 4 is a longitudinal section of the ball-and-socket joint at the front of the main frame, on an enlarged scale. Fig. 5 is an elevation of the spherical knuckle of the connecting-bar. Fig. 6 is a sectional elevation of the spring by which the shoe is supported. Fig. 7 is a perspective view showing a modified construction of my improvement.

Like letters of reference refer to like parts in the several figures.

40 A represents the main frame, *a* the axle supported therein, and *A'* the wheels mounted on the axle.

B is the tongue, rigidly secured to a plate or socket, *b*, extending forwardly from the main frame *A*.

C represents the casing which is attached to the main frame, and which incloses the gear-wheels, whereby motion is imparted from the axle *a* to the longitudinal driving-shaft *c* in a well-known manner. The driving-shaft *c* is supported in a forwardly-extending bearing,

c', which is formed on the main frame *A* and connected with the front end of the plate *b* by a curved bar, *b'*.

D represents the crank-wheel, which is 55 mounted on the front end of the driving-shaft *c*, and *d* is the connecting rod or pitman, which extends from the crank-pin *d'* of the wheel *D* to the cutter-bar *d''*.

E represents the shoe, which supports the 60 inner end of the cutter mechanism.

F represents the front portion of the main frame, which extends forwardly beyond the crank-wheel *D* and connecting-rod *d*; and *G* is a connecting-bar which extends from the 65 front portion, *F*, of the main frame *A* to the shoe *E*, to which it is pivoted at *e* in advance of the cutter-bar *d''*. The connecting-bar *G* is straight, and extends across the machine in front of the connecting-rod *d*, nearly parallel 70 with the latter, and serves, in addition to its usual function, the further purpose of protecting the connecting-rod against stones, grain, grass, or other substances which may lie in the path of the machine.

75 *g* represents a spherical head or knuckle formed at the end of the connecting-bar *G* and seated in a spherical socket in the front portion of the main frame *A*. This socket is composed of a hemispherical socket, *g'*, formed in 80 the front side of the front portion, *F*; and a hemispherical socket, *h*, formed in a hemispherical cap, *H*, which latter covers the front half of the spherical knuckle *g*.

I represents a horizontal fastening-bolt, 85 which secures the cap *H* to the frame portion *F*, and passes through an opening, *i*, in the knuckle *g*. This opening is made flaring from the center of the knuckle to both ends, as represented in Figs. 4 and 5, so that the connecting-bar *G* is capable of a limited rocking motion in the spherical socket and about its longitudinal axis, while at the same time it can be raised and lowered by swinging it on the fastening-bolt *I* as a fulcrum. This construction of the knuckle and socket forms a very durable means of adjustably attaching the connecting-bar to the main frame, as the strains are substantially received by the fastening-bolt, and the cast portions of the socket 95 are to a large extent thereby relieved from said strains.

J represents a diagonal thrust-bar, which is pivoted at its rear end to the main frame A at j, preferably in line with the axis of the ball-and-socket joint at the front end of the main frame. The front or outer end of the thrust-bar J is provided with a bearing, j', which embraces the outer end of the connecting-bar G and supports the same. The portion of the connecting-bar which rests in the bearing j' is made cylindrical, so that the connecting-bar G can be turned in this bearing as it is adjusted.

k is a fixed collar on the connecting-bar G, bearing against the outer side of the bearing j'; and k' is a removable collar, which is applied to the connecting-bar G, on the inner side of the bearing j', thereby confining the latter between these two collars.

K represents an arm forming an upward continuation of the collar k.

L represents a hand-lever, pivoted at l to a notched segment, l', which is secured to the main frame A. The short arm l' of this lever is connected by a rod, l'', with the arm K, so that by moving the lever forwardly or backwardly the connecting-bar G is turned in its bearings and the front edge of the cutter mechanism depressed or raised, as may be desired. The hand-lever L is provided with a suitable spring-catch, m, which engages with the notched segment l', and whereby the lever is locked in any desired position. The notched segment l' may be mounted on the thrust-bar J, and the hand-lever L may be secured directly to the connecting-bar G, as represented in Fig. 7.

N represents a hand-lever, which is pivoted at n to the tongue B; and n' is a notched segment secured to the tongue and adapted to receive a spring-catch, n'', attached to the lever N.

o represents the short arm of the lever N, and P represents a spring whereby the arm o is connected with the front end of the thrust-bar J. The spring P is preferably constructed in the form of a coiled spring seated between two disks, p p'. The lower disk, p', is attached to the arm o by a bail p'', which is secured to the disk and extends upwardly through the spring and the upper disk, p. The latter is connected with the thrust-bar J by a rod, p'', secured with its upper end to the disk p,

and extending downwardly through the lower disk, p'.

The hand-lever N is so adjusted that the spring P supports the weight of the thrust-bar J and connecting parts, thereby relieving the shoe E from this weight, preventing the shoe from dragging on the ground under an excessive weight, and rendering the movements of the machine easy.

I claim as my invention—

1. The combination, with the main frame, of a straight connecting-bar pivoted to the front end of the main frame so as to be capable of a vertical and rolling movement, a thrust-bar pivoted at one end to the main frame and provided at its opposite end with a bearing in which the free end of the connecting-bar is supported and allowed to rotate, a shoe hinged to the free end of the connecting-bar in advance of the cutter-bar, and a hand-lever for imparting a rotary adjustment to the connecting-bar, substantially as set forth. 75

2. The combination, with the main frame and the pitman for operating the cutter, of a straight connecting-bar arranged in front of the pitman and attached to the front end of the main frame by a ball-and-socket joint, a thrust-bar pivoted at one end to the main frame and provided at its opposite end with a bearing in which the free end of the connecting-bar is supported so as to be capable of turning therein, mechanism whereby a rolling adjustment is imparted to the connecting-bar, and a shoe hinged to the connecting-bar in advance of the cutter-bar, substantially as set forth. 80 85

3. The combination, with the main frame and tongue, of a connecting-bar and thrust-bar pivoted to the main frame and connected at their opposite ends, a shoe pivoted to the connecting-bar, a hand-lever mounted on the tongue, and a spring connecting the hand-lever with the thrust-bar, substantially as set forth. 90 95

Witness my hand this 27th day of March, 1884.

CHRISTOPHER C. BRADLEY.
